PROCESS FOR THE TREATMENT OF HYDRO-CARBON OIL

Rodney V. Shankland, Hammond, Ind., and Ralph H. Price, Galveston, Tex., assignors to Standard Oil Company (Indiana), Chicago, Ill., a corporation of Indiana

Application May 23, 1934, Serial No. 727,045

7 Claims. (Cl. 196—49)

This invention relates to processes and apparatus for the treatment of hydrocarbon oil and more particularly to the production of lower boiling point oil from higher boiling point oil.

5 It is an object of our invention to provide an improved plural stage cracking process for producing gasoline of high anti-knock value from heavier hydrocarbon oil, whereby the heavy oil to be treated is first subjected to a preliminary 10 distilling operation wherein light clean gas oil, relatively free from coke-forming tendencies, is separated from heavier products, any gasoline constituents present in the heavy oil also being segregated in this operation; the light gas oil 15 is subsequently subjected to a single pass cracking step wherein a relatively large percentage of conversion to products in the gasoline boiling range takes place rapidly under relatively high temperature and high pressure conditions, and the 20 resulting cracked products are separated into a light final distillate and an intermediate condensate stock; the heavy residual products from the preliminary distilling operation are subjected to a viscosity breaking cracking operation where- 25 to in clean gas oil is produced; and this gas oil in mixture with the intermediate condensate stock from the single pass cracking step, is there- 30 after cyclically cracked to completion at relatively low cracking per pass in a separate low pressure high temperature cracking operation. If desired a heavy gas oil cut may also be segregated from the products formed by the viscosity 35 breaking operation, and returned, in mixture with a similar cut of heavy gas oil derived from the single pass cracking step, to the viscosity breaking operation for further conversion.

In accordance with our invention the heavy oil to be treated, for example crude oil, is first subjected to a preliminary distilling operation 40 wherein gasoline constituents, light clean gas oil, and reduced crude are separated. The light clean gas oil is then subjected to a drastic cracking operation, by being passed once through a primary cracking zone at a relatively high temperature and under a relatively high pressure, whereby a large amount of conversion to products in the gasoline boiling range takes place quickly, for example, such as to produce 30% or more of 420° E. P. gasoline. The cracked products from 45 this once-through operation are thereafter passed to an evaporator tower wherein the lighter products are separated as vapors from liquid tar-like residue, these lighter products being subsequently fractionated in a bubble tower or similar 50 device to produce an intermediate condensate

stock suitable for further cracking, preferably under low pressure in the vapor phase, and a final distillate. The reduced crude is simultaneously subjected to a preliminary viscosity breaking cracking operation, such as to produce 5 clean gas oil with only a relatively small accompanying production of products in the gasoline boiling range, e. g. 8% to 20% per pass. The resulting cracked products are separated into heavy tar-like residue, a clean gas oil suitable for vapor 10 phase cracking and gasoline. A heavier gas oil, not suitable for vapor phase cracking, may also be separated if desired, and be recycled to the viscosity breaking cracking operation. The clean 15 gas oil derived from the viscosity breaking operation, mixed with the intermediate condensate stock derived from the primary drastic cracking operation, is subsequently cyclically cracked to completion in the vapor phase in a secondary zone at a relatively high temperature and, at 20 relatively low pressure, the amount of cracking to products in the gasoline boiling range, per pass, being lower than that taking place in the primary zone.

The vapor phase cracked products are either 25 fractionated to produce a final distillate, and condensate for further recycling through the vapor phase cracking zone, or are combined with the primary or high pressure stage cracked products for fractionation therewith. In the event that 30 the vapor phase or low pressure cracked products are separately fractionated, the final distillate may be combined with that produced by the fractionation of the high pressure cracked products resulting from the once-through cracking 35 operation, the gasoline derived from the viscosity breaking cracking operation, and the gasoline derived from the distilling operation, or if desired other blends of the light final distillates may be made to produce a final product of de- 40 sired characteristics.

Important conditions of this invention are that the gas oil separated in the preliminary distilling operation should be so light as to be relatively free from coke forming tendencies, e. g., 45 of a maximum end point in the neighborhood of 675°-700° F., the heavier ends of the charging stock being treated by the viscosity breaking operation; and that the temperatures and pressures of the primary and secondary cracking 50 zones, and time of passage of the oil there-through, should be selected to produce high cracking per pass in the primary single pass zone and relatively low cracking per pass in the secondary recycling zone. The values to be used 55

depend upon the characteristics of the charging stock, the temperatures of the primary single pass zone being, for example, from 850° to 985° F., or even higher where a very clean stock, e. g., a redistilled low end point stock, is used, and the pressure being from 500 to 2000 pounds per square inch, or more. The secondary recycling zone may operate under a temperature of from 875° to 1100° F., and a pressure of from 50 to 400 pounds per square inch. The viscosity breaking cracking zone is operated under such conditions of temperature, pressure and time as to cause only a relatively small amount of conversion to products in the gasoline boiling range, per pass, while at the same time causing the cracking of the relatively heavy charging stock to produce relatively large quantities of clean gas oil cracking stock suitable for cracking in the vapor phase cracking zone. For example, the temperature may be from 840° to 890° F., preferably about 850° F., and the pressure is most suitably in the range of from 150 pounds per square inch to 300 pounds per square inch, preferably about 230 pounds per square inch. The viscosity breaking cracking operation serves to form a relatively large percentage of clean gas oil which is suitable as charging stock for the vapor phase cracking operation carried out in the secondary or vapor phase recycling cracking zone. This gas oil and also any gasoline formed are removed from the cracked products directly upon the discharge thereof from the viscosity breaking cracking zone so that in the event recycling is carried out only heavy gas oil is returned for further cracking in the viscosity breaking zone.

As a result of the drastic cracking in the primary single pass zone under high temperature and high pressure, of the light clean gas oil separated in the preliminary distilling operation, a final distillate gasoline is produced having a high anti-knock value, and the mixture of clean gas oil from the viscosity breaking operation and the intermediate condensate stock from the primary single pass cracking operation, when cyclically cracked to completion in the secondary cracking zone under high temperature and low pressure, produces a final distillate gasoline also of high anti-knock value, which may be blended with the distillate first mentioned. The anti-knock value of the final product can be increased still more by reforming virgin heavy naphtha, viscosity breaker naphtha or both, and blending resulting gasoline distillate with the other distillates mentioned.

The above mentioned and further objects and advantages of our invention, and the manner of attaining them, will be more fully explained in the following description taken in conjunction with the accompanying drawing.

In the drawing, the single figure is a diagrammatic view of an oil treating system embodying our invention.

Referring more particularly to the drawing, reference numeral 1 indicates a charging line through which fresh charge, such as Mid-Continent crude, reduced crude, heavy gas oil, or the like, is forced by pump 2, traveling through heat exchange coils 3 and 4 having the usual control valves, into stripping tower 5, of any well known type, wherein the heavy charge is distilled in the well known manner to segregate gasoline constituents and light clean gas oil as vapors, from liquid reduced crude, or other heavy liquid oil where the charging stock is not crude oil. The gasoline vapors pass off from the top of the tower through vapor line 6 into condenser 7 from

which the resulting condensate passes to receiver 8. The light clean gas oil, relatively free from coke forming tendencies, is condensed and collected on trap-out tray 9, to form a distillate having an end point of, preferably, from 675° to 700° F. or thereabouts, from which it is removed through pipe 10 and forced by pump 11 through the coils of high pressure heater 12, leaving them preferably at a temperature of about 950° F. and a pressure approximating 750 pounds per square inch, and traveling through pipe 13 into reaction chamber 14. After being soaked in the reaction chamber, the resulting cracked products pass through a conduit 15 into the base of evaporator 16, wherein separation of the cracked products takes place with the result that lighter vapors pass overhead through a vapor line 17 into fractionator 18, tar residuum being withdrawn through line 19. The evaporator 16 may be supplied with baffle plates or similar devices 20 which serve to prevent entrainment of tar in the evolved vapors and with a trap-out tray 21 which serves to collect heavy gas oil such as requires viscosity breaking treatment. The heat exchange coil 4 serves to provide cooling for refluxing purposes, or other suitable conventional refluxing means may be used if desired. This evaporator is most desirably operated at a pressure lower than that of the reaction chamber 14, for example 125 pounds per square inch, the reduction in pressure being insured by pressure reducing valve 22 located in the conduit 15 connecting the evaporator and reaction chamber. If desired the reaction chamber may be by-passed by proper manipulation of valves 23, 24, and 25.

In the fractionator 18 the vapors are separated into a light vaporous portion, e. g. gasoline vapors, which passes overhead through vapor line 26 and condenser 27, resulting condensate being collected in receiver 28, and intermediate condensate stock which is drawn off from the bottom of the tower through a conduit 29 for treatment in the secondary cracking zone.

Reduced crude or other heavy unvaporized stock is withdrawn from the bottom of stripper 5 through pipe 30 and is forced by pump 31 through the coils of viscosity breaking heater 32. In this heater the heavy stock is subjected to cracking of a viscosity breaking nature, such, for example, as to cause a conversion to products in the gasoline boiling range, of 8% to 20% per pass. The temperature of the oil emerging from the heater is preferably about 850° F., and the pressure thereon preferably about 230 pounds per square inch, these conditions corresponding to cracking of about 8% to 10% per pass. Higher temperature, such as 875°-890° F., and/or longer times of contact or heatings will be necessary to secure cracking per pass at a value as high as 20%. In the heating steps the times of passage of the oil through the heating coils are preferably such that little or no coke will be deposited therein.

The hot cracked products pass through the line 33 and control valve 34 into evaporator 35, which may be equipped with fractionating elements, such as baffles 36, or the like, the necessary reflux being supplied by any suitable means, for example, cooling coil 37. In this vessel, which may be held at the same or lower pressure than the coils of viscosity breaking heater 32, the hot cracked products separate into vapors which pass off overhead through vapor line 38 into fractionator 39, and liquid residue which is withdrawn 75

through line 40. In the fractionator 39 the introduced vapors are subjected to fractionation in the usual well known manner, vapors of the desired end point, e. g. gasoline, passing overhead 5 through line 41 into condenser 42 and resulting condensate being collected in receiver 43. Cooling for refluxing purposes may be supplied in any suitable manner, for example by means of the heat exchange coil 44. Reflux condensate, being 10 clean gas oil, is withdrawn from the base of the fractionator 39 through pipe 45 and is forced by pump 46 through the coils of secondary vapor phase heater 47, in mixture with the intermediate condensate withdrawn from the base of fractionator 18 through pipe 29. The hot cracked products emerge from the coils of the secondary vapor phase heater 47 at a vapor phase cracking temperature of preferably more than 900° F., for example 950° F., under a relatively low pressure 15 such as 175 pounds per square inch, and pass through transfer line 55 into reaction chamber or digester 56, preferably under substantially the same pressure. The amount of cracking per pass through the secondary vapor phase cracking zone 20 is preferably lower than that in the primary cracking zone, most suitably around 18%, although it may range from 10% to 25%. Part or all of this cracking may take place in the heater 47 itself, the digester 56 being by-passed if desired, by operation of valves 51, 58, and 59. The digested products pass from the reaction chamber through vapor line 60 and reducing valve 61 into evaporator 62. The evaporator is preferably maintained at a pressure considerably lower 25 than that of the reaction chamber, for example, 50 pounds per square inch. The evaporator 35 may be provided with a trap-out tray 47' for collecting heavy gas oil which should be subjected to further viscosity breaking treatment. This 30 condensate is withdrawn through line 48 and forced by pump 49 through the coils of viscosity breaking heater 32, in mixture with the reduced crude from stripper 5, and also heavy condensate withdrawn from trap-out tray 21 of evaporator 45 16, by way of conduit 50 having pump 51. If desired additional viscosity breaking cracking may be accomplished by means of a reaction chamber 52 which may be placed in operation by proper adjustment of valves 34, 53, and 54. 50 This reaction chamber is particularly useful in obtaining the higher percentages of cracking per pass mentioned hereinbefore.

Light vapors pass off from the top of the evaporator 62 through vapor line 63, which introduces them into the base of fractionator 64, while liquid tar residue collecting in the bottom of the evaporator is withdrawn through draw-off line 65. In the fractionator 64 the vapors are separated into a light vapor fraction of the desired 60 end point, e. g. gasoline, which passes through the vapor line 66 into condenser 67, the resulting condensate being collected in receiver 68, and reflux condensate which collects in the base of the fractionator. Distillate deposited in the 65 receiver 68 has the desired end point and may either be used separately or be blended with the distillate from the receivers 8, 28, and 43, or some of them, the lines 69, 70, 71, and 72 being provided for this purpose, resulting blended distillate being collected in storage drum 73 if desired. Draw-off lines 74, 75, 76, and 77 are furnished so that the several distillates may be drawn off 70 individually. Reflux condensate is withdrawn from the base of the fractionator 64 through conduit 78 having pump 79, preferably being forced

through the coils of the secondary heater 47, along with charge introduced either through line 45 or line 29 or through both, this recycling of the reflux condensate serving to cause additional cracking thereof. 5

Reference numerals 80, 81, and 82 indicate draw-off lines whereby, if desired, quantities of condensate collecting in the fractionators 18, 39, and 64, respectively, may be diverted from the process in order to establish any selected balance 10 of conditions. These condensates are suitable as distillate fuel oil, or may be used in cutting tars drawn off from the process, to desired viscosity for use as fuel oil. In place of the cooling coils in the various towers or in cooperation with the 15 coils, direct cooling may be employed by pumping back distillate or other cooling mediums in the customary manner, by suitable means (not shown). Cross-over line 84 and valves 85 and 86 are provided so that the evaporator 35 and fractionator 39 may be cut out of circuit, the cracked products from the viscosity breaking zone being passed directly to the evaporator 16, if desired. This flow, which may be accomplished by closing valve 86 and opening valve 85, results in the liquid 20 residues and heavy gas oils and light gas oils from the primary high pressure cracking operation and viscosity breaking cracking operation being combined and treated as a mixture. No further description of this alternative method 25 of operation seems necessary. In like manner the fractionator 39 alone may be eliminated, evaporator 35 still being used, by closing valve 95 and opening valve 96 in cross-over line 97, thereby 30 directing the vapors from evaporator 35 into fractionator 18. 35

Instead of utilizing two different fractionators for the primary high pressure and the secondary vapor phase portions of the systems a single fractionator alone may be used, cross-over line 87 40 being provided so that vapors from the evaporator 62 can be directed into fractionator 18. When this manner of operation is desired valve 88 is closed and valve 89 is opened. When operating in this manner the final distillates from both the 45 primary high pressure system and the secondary vapor phase system are collected together in the receiver 28. Even more apparatus may be eliminated if separate residue draw-off lines are not desired, by introducing the digested products from 50 reaction chamber 56 directly into evaporator 16, this operation being effected by means of cross-over line 90 and valves 91 and 61. Upon closure of valve 61, and opening of valve 91 the vapor phase digested products are diverted into the 55 evaporator 16. This manner of operation causes the mixing of the residues from both the secondary vapor phase cracking operation and the primary high pressure cracking operation, the mixed residue being withdrawn through line 19. 60

Additional light clean oil for cracking in the primary high pressure heater 12 may be supplied through charging line 93, this oil being for example, a light virgin gas oil from an external source. Additional heavy oil may be supplied to 65 the viscosity breaking operation from an external source through line 94.

In order to obtain increased anti-knock value of the final gasoline distillate of the process, a cut of heavy virgin naphtha may be removed from 70 the stripper 5, after having been collected on trap-out tray 100, and passed by way of line 101 through a separate reforming coil located in the secondary vapor phase furnace 47, in which it is subjected to a conventional reforming operation, 75

for example one carried out at a temperature in excess of 950° F. and a pressure of, for example, 700 pounds per square inch or more. The resulting reformed products may be passed into the 5 evaporator 62 through line 104 having pressure control valve 105. If desired vis-breaker naphtha may be collected on a trap-out tray 102 in the fractionator 39 and passed through line 103 into the reforming coil in the furnace 47, either alone 10 or in mixture with virgin heavy naphtha collected on the trap-out tray 100 of the stripper 5. The illustrative temperature and pressure given for the reforming operation are not intended to be taken as invariable since different conditions 15 of temperature and pressure may be used for producing different degrees of reformation. The reforming coil might also be located in either of the furnaces 12 or 32, or in a separate furnace if desired, the only requisite being that the necessary temperature be attained. Alternatively 20 the reforming coil might discharge into one of the other evaporators of the system.

Operation

25 In operation heavy charging stock such as crude oil, reduced crude or heavy gas oil, e. g., 37° A. P. I. Mid-Continent crude, is preheated to a distilling temperature in any suitable manner, for example by passage through the heat 30 exchange coils 3 and 4 in fractionator 18 and evaporator 16, respectively, and is then subjected to a conventional stripping operation, for example in a tower such as 5, with the resulting segregation of the crude or other charging stock, 35 into reduced crude or other liquid residue, which collects in the base of the stripper tower 5, a light clean gas oil condensate, preferably having an end point of from 675°-700° F., which collects on trap-out tray 9 and may be introduced 40 directly into the primary high-pressure heater 12 by way of line 10, and a light distillate of lower boiling characteristics than desired for treatment in the high-pressure heater. This light distillate, which is collected in receiver 8, would fall 45 in the gasoline boiling range.

The reduced crude or liquid residue collecting in the base of the stripper tower 5 is withdrawn through line 30 and introduced into the coils of viscosity breaking heater 32. In this heater the 50 heavy reduced crude is cracked sufficiently to produce from 8% to 20%, e. g., 8% to 10%, of products in the gasoline boiling range, and resulting cracked products are introduced into the evaporator 35, after passage through the reaction 55 chamber 52, or not, as desired. The cracking conditions in the heater 32 may be a temperature of from 840° to 890° F., preferably about 850° F., and a pressure of from 150 to 300 pounds per square inch, preferably about 230 pounds per 60 square inch. The desired amount of cracking may be accomplished partially in the viscosity breaking heater and partially in the reaction chamber 52, or wholly in the heater alone, the reaction chamber being by-passed and correspondingly higher temperatures being employed 65 in heater 32. In the evaporator, which may be held at the same or a lower pressure than that of the heater, the products separate into vapors and a liquid residue, the former passing upwardly 70 through the tower and being partially fractionated therein, while the latter is withdrawn from the bottom of the tower through line 40. The partially fractionated vapors pass through vapor line 38 into fractionator 39, wherein they are 75 completely fractionated in the usual manner, the

fractionated vapors passing off from the top thereof and being collected in receiver 43 as a gasoline distillate suitable for blending to produce a final desired product. A side cut of heavy gas oil collects on trap-out tray 47 and is preferably 5 recycled through the viscosity breaking heater 32 for further conversion.

The light clean gas oil withdrawn as a side stream from stripper 5 passes through the primary high pressure cracking heater 12, which operates on a once-through basis without recycling. In this heater the oil is subjected to a high temperature, preferably in excess of 900° F., e. g., 950° F., under a high pressure such as 750 pounds per square inch, and the heated products are 15 then transferred to the reaction chamber 14 wherein additional conversion takes place, the conditions of temperature and pressure already mentioned being regulated to cause cracking to an extent of from 35% to 55%, or more, per pass 20 through the heater and reaction chamber, or heater alone if the reaction chamber be bypassed, for example 45 or 50%. After leaving the reaction chamber the cracked products pass to the evaporator 16, the pressure in the evaporator being held at a lower value, which may approximate 125 pounds per square inch, by action 25 of pressure reducing valve 22 in the transfer pipe 15 through which the products travel from the reaction chamber to the evaporator. 30

In the evaporator the introduced products, being under lower pressure and at a suitable temperature such as 800° to 825° F., separate into a vapor portion which passes overhead through vapor line 17 into fractionator 18, and a liquid 35 residue portion which is drawn off through pipe 19. The fractionator 18 is provided with bubble plates and caps or similar fractionating devices, and serves in the well known manner to separate the vapors into an intermediate reflux condensate suitable for further cracking which collects 40 in the base of the fractionator, and a light vapor portion, e. g. gasoline, having the desired boiling characteristics, which passes overhead and is then condensed and collected in receiver 28. 45

The intermediate condensate oil is drawn off through the conduit 29 and, in mixture with reflux condensate from the base of fractionator 39, is passed through secondary vapor phase cracking heater 47, wherein it is raised to a temperature preferably in excess of 900° F., for example 950° F., under a relatively low pressure such as 175 pounds per square inch, which is preferably the same as that prevailing in the digester 56 into which the cracked products are subsequently introduced. The amount of cracking per pass through the vapor phase system is relatively low, preferably around 18%, although the conversion may range from 10% to 25%. The hot cracked products pass from the secondary vapor phase 60 heater into digester or reaction chamber 56, and there undergo further conversion, the digested products being passed through line 60 into evaporator 62, which is maintained at a still lower pressure, such as 50 pounds per square inch, 65 by action of the pressure reducing valve 61. Alternatively digester 56 may be bypassed by opening valve 58 and closing valves 57 and 59. Light vapors travel from the evaporator through vapor line 63, which introduces them into the bottom 70 of fractionator 64, while the liquid tar residue collecting in the base of the evaporator is removed through line 65.

In the fractionator 64 the vapors are separated into a light fraction of the desired boiling char- 75

acteristics, which passes off from the top thereof and is collected as a distillate of desired end point, or of desired blending characteristics, e. g. gasoline, in receiver 68, and a reflux condensate that collects in the base of the fractionator. This 5 reflux condensate is preferably recycled through line 78 for further cracking in the heater 41.

Additional heavy charging stock may be introduced through line 94 and additional light 10 clean charging stock may be introduced through line 93, if desired, both of these stocks being derived from external sources. Likewise, portions 15 of the reflux condensate from fractionators 18, 39, and 64 may be diverted from the process through lines 80, 81, and 82 to effect any desired 20 balance of operating conditions. The several light gasoline distillates formed in the different parts of the combined process may be withdrawn separately or may be blended to produce a gasoline of predetermined characteristics, the 25 blending being accomplished by way of lines 69, 70, 71, and 72, the blended distillate being collected in gasoline storage drum 73.

Instead of using separate evaporators and fractionators for the secondary vapor phase stage as assumed in the preceding description of the operation, valve 61 may be closed and valve 91 opened thereby directing all of the products into evaporator 16. In this event all of the gasoline 30 from both of these stages would be collected in receiver 28. Instead of using a single evaporator, the secondary vapor phase products may be permitted to pass into evaporator 62 and the vapors therefrom may be diverted into the fractionator 18 by the closing of valve 88 and opening 35 of valve 89. This latter method of operation would eliminate one fractionator and its accessories, while permitting the drawing off of tar separately from each stage. A further reduction 40 in the quantity of apparatus used may be effected by diverting the viscosity breaker products into the evaporator 16, this being accomplished by closing valve 86 and opening valve 85. Alternatively the evaporator 35 may be utilized 45 and the fractionator 39 eliminated, by closing valve 95 and opening valve 96. This arrangement of crossover pipes and valves permits flexible 50 operation of the system, enabling separation and fractionation to be carried out in separate towers or permitting the viscosity broken products to be treated with the high pressure cracked products and with the vapor phase cracked products, or enabling the viscosity broken products 55 to be treated separately and the high pressure cracked products and the vapor phase cracked products treated together.

The tar withdrawn from the several evaporators through draw-off lines 19, 40, and 65 may be cut back with condensate stock withdrawn 60 through any of draw-off lines 80, 81, and 82, if desired, the condensate withdrawn through line 82 from the base of fractionator 64 being particularly suitable for this purpose. When operating in this manner heavier tars may be produced in 65 the evaporators 16, 35, and 62, while still permitting the formation from these heavy tars of fuel oil of desired viscosity. Alternatively the condensate stocks withdrawn may be used separately as light distillate fuels.

If desired heavy virgin naphtha from trap-out tray 100 in stripper 5 or heavy vis-breaker naphtha from trap-out tray 102 of fractionator 70 75 may be subjected to reformation either individually or in mixture, by passage through the reforming coil located in one of the several fur-

naces shown, for example in furnace 47, or in a separate furnace if desired. In passage through this reforming coil the naphtha is raised to a suitable reforming temperature, for example, a temperature of from 950° to 1050° F., under a 5 pressure of, for example, 500 pounds to 1000 pounds per square inch, more or less, the resulting reformed products being introduced into the evaporator 62, after having been reduced in pressure if desired, by action of reducing valve 105. 10 Alternatively, the reformed products might be introduced into one of the other evaporators.

Our invention as described hereinbefore permits the production from relatively heavy charging stock having marked coke-forming tendencies, of a relatively large quantity of high anti-knock gasoline, the preliminary distilling step serving to produce a relatively clean cracking stock of small coke-forming tendencies suitable for very high cracking per pass in the primary 20 high pressure stage wherein, since the cracking is carried out under high pressure and high temperature gas production is minimized as a result. Likewise as the cracking is done rapidly tar does not have much chance to form. In the subsequent 25 cracking of the intermediate condensate from the high pressure stage, in the following secondary vapor phase stage, tar formation is still further retarded and, since a large part of the lighter products produced has already been removed in the high pressure operation, the total loss of desired distillate due to the secondary cracking is small, being essentially only that which occurs in the low pressure cracking operation. The viscosity breaking step permits the 30 heavy residual stock which is undesirable from a coke-forming viewpoint for treatment in the primary high pressure heater, to be converted into cracking stock suitable for further conversion in the vapor phase in mixture with the intermediate condensate from the primary cracking operation. 35

The expression "cracking per pass" used throughout this specification refers to the percentage of conversion to end point gasoline of the 40 stock passing into the conversion zone, in a single pass therethrough.

This specification describes certain specific embodiments of our invention but the scope of the invention is not intended to be limited thereto 50 except as set forth in the accompanying claims. Thus, we may obtain higher cracking per pass, in the primary cracking stage than that set forth, particularly when using higher pressure, such as pressures of 1500-2000 lbs. per square inch. 55 These high degrees of conversion are a distinctive feature of our invention and to them we ascribe in large measure the success of the process.

We claim:

1. The process of treating hydrocarbon oil which comprises heating crude oil to a distilling temperature to cause vaporization of lighter constituents thereof and leave liquid reduced crude, fractionally condensing the vaporized lighter constituents to segregate a heavy naphtha condensate, and a light clean gas oil condensate relatively free from coke-forming tendencies, heating said clean gas oil condensate to a relatively high cracking temperature in a primary cracking 70 zone under relatively high pressure, for a sufficient length of time to cause a high degree of cracking thereof, separating resulting cracked products into vapors and a liquid residue, in a first separating zone, fractionating said vapors to 75

form a desired gasoline distillate and an intermediate gas oil condensate, preventing the return of said intermediate condensate to said high-temperature cracking zone, simultaneously passing said reduced crude first-mentioned through a viscosity breaking cracking zone wherein it is raised to a moderate cracking temperature and subjected to a viscosity breaking cracking operation, separating the resulting lightly cracked products into vapors and a liquid residue, fractionating said vapors to form a desired gasoline distillate and reflux condensate, combining said intermediate condensate and said reflux condensate, and passing the mixture through a secondary vapor phase cracking zone wherein it is raised to a vapor phase cracking temperature and subjected to a moderate amount of cracking per pass, introducing the resulting moderately cracked products into a second separating zone wherein separation thereof into vapors and a liquid residue occurs, fractionating said vapors to form a desired gasoline distillate and a reflux condensate, returning said reflux last-mentioned to said secondary vapor phase cracking zone for further cracking, simultaneously passing said heavy naphtha condensate through a separate reforming zone wherein it is raised to a cracking temperature and subjected to reformation, and introducing the resulting reformed products into said second separating zone.

2. The process of treating hydrocarbon oil which comprises heating crude oil to a distilling temperature to cause vaporization of lighter constituents thereof, including light clean gas oil, and leave liquid reduced crude, condensing said light clean gas oil to form a clean charging stock, relatively free from coke-forming tendencies, heating said clean charging stock to a relatively high cracking temperature in a primary cracking zone, under relatively high pressure, for a sufficient length of time to cause a high degree of cracking thereof, separating resulting cracked products into vapors and a liquid residue, in a first separating zone, fractionating said vapors in a first fractionating zone to form a desired gasoline distillate and an intermediate gas oil condensate, preventing the return of said intermediate condensate to said high-temperature cracking zone, simultaneously passing said reduced crude first-mentioned through a viscosity breaking cracking zone wherein it is raised to a moderate cracking temperature and subjected to a viscosity breaking cracking operation, separating the resulting lightly cracked products into vapors and a liquid residue, in a second separating zone, fractionating said vapors in a second fractionating zone to form a desired gasoline distillate, a heavy naphtha condensate and a clean gas oil condensate, combining said intermediate condensate and said clean gas oil condensate and passing the mixture through a secondary vapor phase cracking zone wherein it is raised to a vapor phase cracking temperature and subjected to a moderate amount of cracking per pass, separating the resulting moderately cracked products into vapors and a liquid residue in a third separating zone, fractionating said vapors in a third fractionating zone to form a desired gasoline distillate and a reflux condensate,

5
sate, and simultaneously passing said heavy naphtha condensate through a separate reforming zone wherein it is raised to a cracking temperature and subjected to reformation and introducing the resulting cracked products into said third separating zone.

3. The process of treating hydrocarbon oil which comprises passing a relatively light clean gas oil through a primary cracking zone wherein it is raised to a relatively high cracking temperature and subjected to conversion, introducing the resulting cracked products into a separating zone wherein vapors separate from liquid residue, passing resulting vapors to a first fractionating zone wherein fractional condensation thereof occurs and constituents heavier than desired in the final product are condensed as a reflux condensate, removing the fractionated vapors and condensing them as a desired product, simultaneously passing a relatively heavy oil, not suitable for use as clean cracking stock, through a viscosity breaking cracking zone wherein it is raised to a cracking temperature and subjected to conversion, introducing the resulting cracked products into a second separating zone wherein vapors separate from liquid residue, passing the resulting vapors into a second fractionating zone wherein fractional condensation occurs with the formation of a heavy naphtha condensate and a gas oil condensate, removing the fractionated vapors and condensing them as a desired product, removing reflux condensate from said first fractionating zone and gas oil from said second fractionating zone, combining them and passing the mixture through a secondary cracking zone wherein it is raised to a cracking temperature and subjected to conversion, introducing the resulting cracked products into a third separating zone wherein vapors separate from liquid residue, fractionating the resulting vapors to form an additional quantity of final desired distillate, and simultaneously passing said heavy naphtha condensate through a separate reforming zone wherein it is raised to a cracking temperature and subjected to conversion, and introducing the resulting reformed products into said third separating zone.

4. A process in accordance with claim 3 wherein the vapors separated in said third separating zone are fractionated in a fourth fractionating zone.

5. A process in accordance with claim 3 wherein the vapors separated in said third separating zone are fractionated in said first fractionating zone.

6. A process in accordance with claim 3 wherein the vapors separated in said third separating zone are fractionated in a third fractionating zone wherein a reflux condensate is formed and said reflux condensate is recycled through said secondary cracking zone for further conversion.

7. A process in accordance with claim 3 wherein during the fractionation of the vapors separated in the first separating zone a relatively heavy condensate is formed and this condensate forms a source of the relatively heavy oil passed through the viscosity breaking cracking zone.
